FINGER RING OR THE LIKE

Abe Hoffenberg, 215 W. 5th St.,
Los Angeles, Calif. 90013

Filed Aug. 12, 1968, Ser. No. 13,091

Term of patent 14 years

Int. Cl. D11—01
U.S. Cl. D45—10

FIG. 1.

FIG. 2.

FIG. 3.

FIG. 4.

FIG. 5.

FIG. 6.

FIG. 1 is a top plan view of a finger ring showing my new design wherein the inner top space is filled with a series of stones and plain hearts;

FIG. 2 is a side elevational view of the same;

FIG. 3 is an opposite side elevational view of the same;

FIG. 4 is an end elevational view of the same;

FIG. 5 is an opposite end elevational view of the same;

FIG. 6 is a top plan view of the design of FIG. 1 wherein the inner top space is filled with a series of stones only.

I claim:

The ornamental design for a finger ring or the like, substantially as shown and described.
